INVENTOR.

George Kellog.
BY Richard D. Burne.

ATTORNEY.

UNITED STATES PATENT OFFICE.

GEORGE KELLOG, OF NEW YORK, N. Y.

BUTTON.

Application filed July 26, 1923. Serial No. 653,986.

To all whom it may concern:

Be it known that I, GEORGE KELLOG, a citizen of the United States, residing at New York, in the county of New York and 5 State of New York, have invented certain new and useful Improvements in Buttons, of which the following is a specification.

This invention relates to buttons and more particularly to a novel and improved sectional button or fastener which can be attached without sewing the same to the material or garment on which it is to be placed.

One of the objects of my invention is to provide a button wherein the head is provided with a stud or projection which may be forced through the material to receive a threaded cap thereon so as to lock the head and firmly clamp and grip the fabric or material thus eliminating the necessity 20 of sewing the button to the same.

A continued object of my invention is to provide a sectional button of the character above specified which is extremely simple in construction, easily assembled, practical, 25 durable, and otherwise capable of being manufactured at an extremely low cost whereby its commercial possibilities are greatly enhanced.

In the drawings, attached herewith and 30 forming a part of the specification,

Figure 1 is a top plan view.

Figure 2 is a bottom plan view.

Figure 3 is an enlarged sectional view 35 showing the button attached to a piece of fabric.

Referring now to the drawings, wherein like reference characters designate corresponding parts throughout the several views, 40 5 designates the head of the button, having a preferably concaved top surface, which may be of plain material or, if so desired, embroidered, ornamented or designed in any well known manner. The head is formed with a flat bottom surface 6 and centrally 45 thereof, is provided with a truncated projection 7 in the form of a pyramid in which a stud 8 is secured and extends partly into the body portion of the head 5 above referred to. The opposite end of the stud 8

is threaded as indicated at 10 and terminates 50 in a sharp point 11, designed as to be easily forced through the material or fabric when it is desired to position the button. A cap 12, somewhat smaller in diameter than the head 5 is provided with a central, threaded 55 aperture whereby the said cap may be secured on the threaded portion of the stud and thus lock and clamp the material between the projection 7 and the annular surface 13 of the cap. 60

It will be readily understood, that if so desired, the cap 12 may also be ornamented for the obvious purpose.

It will thus be seen that a button of this construction permits of its easy attachment 65 to any part of a garment without sewing the same and since it can be easily detached, without in any way, affecting the material since it is well known that in the removal 70 of buttons or when replacing the same, the fabric is sometimes ripped or torn. A button of this character can easily be attached by simply forcing the pointed end of the stud through the material and threading the cap 12 thereon, thus locking the stud. 75

While I have illustrated and described my invention with some degree of particularity, I realize that in practice various alterations 80 therein may be made. I therefore reserve the right and privilege of changing the form of the details of construction or otherwise altering the arrangement of the correlated parts without departing from the spirit of the invention or the scope of the appended claim. 85

Having thus described my invention, what I claim as new and desire to secure by United States Letters Patent is:—

A button of the class described comprising a head having a truncated, pyramidal shank, a stud secured within the shank, said stud having a threaded portion and a pointed extremity for piercing the material or fabric, and a cap threaded on the stud for fastening the bottom face of the shank to 95 the fabric.

In testimony whereof I affix my signature.

GEORGE KELLOG. [L.S.]
